PAPER FEEDING DEVICE

Walter P. Scharr, Berlin-Lankwitz, Germany, assignor to International Business Machines Corporation, New York, N. Y., a corporation of New York

Application May 24, 1938, Serial No. 209,700
In Germany June 5, 1937

13 Claims. (Cl. 197—133)

This invention relates generally to improvements in paper feeding devices and more particularly to novel controls for bill feeding in record control printing machines.

5 The main object of the invention is the provision of improved devices for controlling the spacing of a continuous record sheet so that bill forms thereon are positioned to receive lines of address print and item print in certain selected areas on 10 the forms. The forms usually contain a pre-printed heading and other printed information which limits the area in which record controlled printing may be received. Record cards are arranged in groups relating to one customer or one 15 source of business and these cards are sensed to control the printing of a bill. However, there are times when the number of cards in a group exceeds the number of lines provided for the reception of such data on one bill form. The devices of 20 the present invention are provided with automatic feeding controls for carrying the extra items over to the proper position on a second form after the capacity of the first form has been reached.

Another object of the invention is the provision 25 of means for automatically printing a progressive total at the end of a form containing an incomplete group of items. A feature of the invention is the automatic spacing of the bill form, either on the occurrence of a group change or on 30 the completion of item printing in the area allotted to it, to present the total print receiving position of the form at the printing line.

Another object of the invention is the provision 35 of flexible controls for the bill feeding devices whereby various arrangements of the address, item and total printing positions may be made by the operator. The feeding devices are adjustable for various lengths of forms and also for preselecting the lines on which address printing 40 is to start, the amount of space to be provided between such address printing and the first line of item printing, the number of lines of item printing to be received on each bill, the spacing between the last item impression and the total, and the distance between the total and the first 45 line of address printing.

A further object of the invention is the provision 50 of electrical controls which may be plugged before the machine is operated to control the arrangement of printing on a bill form. The devices include a commutator, the segments of which are related to the lines on the bill form. Each segment may be made effective by plug connections established by the operator to suit the 55 arrangement desired on the bill. Associated with the commutator are three magnetic clutches, one for controlling the starting and stopping of the feeding devices, the second for connecting the commutator with the feeding devices and the 60 third for resetting the commutator.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 is a sectional elevation view of the magnetic clutches which control and operate the platen spacing means.

Fig. 2 is a detail view of the line selecting commutator.

Fig. 2A is an elevation view of the commutator brush resetting clutch and the line space controlling clutch.

Fig. 3 shows a portion of the continuous record sheet.

Fig. 3A shows a portion of a perforated record card.

Figs. 4 and 4A together form a wiring diagram of the machine.

Fig. 5 is a timing chart showing the sequence of operation of the cam contacts.

Fig. 6 is a perspective view showing one denominational order of the accumulating devices.

Fig. 7 is a sectional elevation view of the printing devices.

The controls for the feeding devices comprise 30 a magnet 1 (Fig. 1) which is energized at differential times to establish a connection between the operating motor 2 (Fig. 4) of the printing machine and the platen 3 (Fig. 1). The holder 4 for the magnet 1 is loosely mounted on a shaft 35 5 and carries a gear 6 meshing with a gear 8 mounted on a shaft 7 which is continuously operated by the motor 2 so that the holder 4 and magnet 1 rotate continuously during operation of the machine. The holder 4 is formed in the 40 shape of a cup in which the magnet 1 is assembled. The edge of the cup holder 4 is provided with a friction clutch ring 4' which is adapted to contact with the side of a gear wheel 9 which is the armature of the magnet 1. Armature gear 9 45 is attached to the shaft 5 so that, when the magnet 1 is energized, the gear is frictionally connected to holder 4 and shaft 7 and transmits the driving movement through shaft 5 to differential gearing 10, 11 and 12 connected to the platen 50 roll 3. The operation of this differential gearing is described in greater detail hereinafter. In order that the holder 4 and the clutch magnet 1 may be effective to drive gear wheel 9, it is made shiftable along the shaft 5 so that, when the 55 magnet is energized, the entire unit shifts axially to the right to contact with armature gear 9.

On this same shaft 5 there is mounted another cup holder 13' containing a clutch magnet 13. This holder 13' is riveted on the armature gear 9 60

and therefore rotates with the shaft 5. The armature of magnet 13 is a disc 14 fixed on a shaft 15 supported at one end by means of a pivot 16 within shaft 5 and carrying at its other end a brush holder 17 with commutator contact brushes 18 and 19. These brushes wipe over a contact ring 21 and separate contact spots 20 arranged in a circle (Fig. 2). Brush 18 cooperates with the separate spots 20 and brush 19 is in constant contact with the continuous ring 21. The spots 20 and ring 21 are embedded in a stationary commutator disc 22 made of insulation material which is fastened to the machine frame 24 by means of screw bolts 23. The contact spots 20 are each formed with a recess or plug socket so that by means of plugs 25 selective connections may be established with the wiping brush devices 18 and 19 as described more fully hereinafter with reference to the wiring diagram.

The armature gear 9 controlled by magnet 1 and the disc 14 controlled by magnet 13 are both under the influence of separate locking devices with which electrical unlocking elements are coordinated. Pawls 30 and 31 (Fig. 2A) cooperate with teeth 28 on armature 9 to prevent movement of the gear in either direction. These pawls are carried by an armature 29 operable to release the pawls when a magnet 26 is energized. The other armature disc 14 is provided with a single ratchet tooth 32 with which pawls 33 and 34 of an armature 35 cooperate as controlled by a magnet 27. Armature 14 and the cooperating stopping means comprising pawls 33 and 34 constitute a single revolution clutch. In Fig. 2A it is seen that energization of magnets 26 and 27 serves to free the armatures 9, 14 so they may rotate as urged by the clutch connections established by the magnets 1 and 13.

Holder 13' is provided with a friction ring 14' for engaging the disc 14 when the magnet 13 is energized. This connection serves to attach the brush holder 17 to the shaft 5 which is rotated when magnet 1 is energized.

A second magnet 36 (Fig. 1) is provided for acting upon the armature disc 14. This magnet 36 is located in a cup holder 36' which is loosely mounted on the shaft 15 and connected by means of gears 37 and 38 with the continuously rotating shaft 7. Holder 36' is provided with a friction ring 37' adapted to cooperate with armature disc 14 to restore it and the connected brush holder 17 to the normal position when magnet 36 is energized.

In order that current may be conveyed to the magnets 1, 13 and 36, the holders in which they are located are provided with pairs of contact rings 39 on which current conducting brushes 40 wipe to provide a continuous path along which the energizing impulses may be carried.

The gearing 10, 11 and 12 between the shaft 5 and the platen 3 is of a differential form permitting the platen to be moved forward or backward during operation of the machine to correct the location of the record sheet should the printing line creep to an inaccurate position. In the normal condition of the parts the large gear 12 carrying the planet gear 12' is locked by a pawl 41 which may be released manually or shaped in the form of a ratchet to permit forward turning of the platen 3 by hand. The operator may grasp the knurled outer surface of the drum 12a attached to gear 12 to rotate the platen manually.

The operation of the devices will now be described with reference to the wiring diagram (Figs. 4 and 4A), assuming that settings have

been made to space the printing on the forms as represented in Fig. 3. It is noted that an example is assumed wherein the number of item cards of the first group exceed the allotted number of item lines provided on one form.

The feed controlling commutator device 22 is proportioned with a capacity of 100 switching points to accommodate forms varying in length up to one hundred line spaces. Therefore, the fixed insulation disk 22 is provided with a hundred contact spots and plug sockets 28 designated "0" to "99". During one complete revolution of brush holder 17 and brush 18, it is possible to effect one hundred different contact closures for initiating starting or stopping of the sheet feeding devices, starting or stopping of the brush moving devices, the resetting of the brush 18, and the printing of a total. Any of these operations may be selected to occur when any line of a form is at the printing point, by merely plugging the control devices to the desired contact spots 20 related to the lines at which a change in feed control is to take place.

For example, in Fig. 3 the forms are seventeen lines in length, with two address lines, a space of five lines to the first line of item print, a space of five lines devoted to item printing and a space of three lines between the last item and the total impression. The spaces between machine controlled printing impressions are used for a pre-printed bill heading and receipt information suitable to the business concerned. Of course, it is understood that any other arrangement of the lines of print may be made on the forms; but assuming that the form described is the one desired, then plug connections are made to the contact spots 20 designated "1", "6", "10", "13" and "17", whereby there is established the time of operation of the various sheet feeding and printing controls about to be described.

Operation of the machine is started by closing the main switch HS (Fig. 4), thereby energizing the brush operating magnet 27 and the clutch magnet 13. Magnet 27 (Fig. 2A) then attracts the armature 35 to disengage the pawl 32 from the disc 14 and armature 35 also closes contacts 27'. At the same time, magnet 13 (Fig. 1) effects an axial movement of the disc 14 and establishes a connection of the brush holder 17 with the continuously rotated shaft 7, providing the magnet 1 is energized to close the clutch connections between holder 4 and armature gear 9. The energization of the magnet 27 is effected by means of a circuit including line 42 (Fig. 4A), contact 22a, wire 43, switch 44, magnet 27, wire 45 and line 46. Magnet 13 is energized over a circuit following a path through line 42, wire 47, upper contacts 22c, switch 48, wiping contacts 39 and 40 at the magnet 13, magnet 13, wire 49 and line 46.

The start key AT (Fig. 4) is then depressed to operate the machine motor by closing a circuit through the motor coupling magnet KM and the motor relay MR. These motor control magnets are maintained in energized condition by the cam contacts L1 and the motor contacts MRb associated with the relay MR. It may be assumed that the record cards are already in the machine so that the well known upper and lower card levers are operated and the associated lever contacts OK5 and UK5 are closed. The magnet KM and relay MR remain energized as long as cards continue to pass through the machine because then whenever the cam contacts L1 open, the card lever contacts OK5 are held closed. Upon energization of the relay MR, 75

the motor 2 starts to rotate and stops only after all cards have been sensed.

During the first machine cycle, the first line of the address is printed before line spacing is effective. This is possible because magnet 26 is not energized during the first machine cycle, since contacts 22a are opened during the preceding cycle of the machine and close only after the cam contacts L34 open during the first cycle.

10 On the second machine cycle; cam contact L31 is closed and magnet 26 is energized by means of the following circuit: line 42, contact 22a, contact 24b, switch 50, contacts VRGe, switch 51, cam contacts L31, lower contacts 21a, magnet 26, and line 46. Magnet 26 (Fig. 2A) then attracts the armature 29 and closes the contacts 26' thereby establishing a circuit through the feeding control magnet 1. The circuit through magnet 1 includes line 42, contacts 22a and 24b, switch 50, wire 52, contacts 26', magnet 1, wiping contacts 39, 40, wire 45, and line 46. The continuously rotating magnet holder 4 (Fig. 1) then grasps the armature gear 9 connected to the shaft 5 and thereby actuates gearing 10, 11 and 12 to turn platen 3. The operation of platen 3 is effective for only one line space because the energization of magnet 26 is so short that the pawls 30, 31 engage the armature gear 9 after one step movement.

30 After the record sheet is line spaced, the second address line is printed. This is done while the brush holder 17 is positioned with the brush 18 (Fig. 4A) contacting the spot 20 designated "1" on the commutator 22. After the second address line is printed, cam contacts L34 close to energize a relay R21 through a circuit including line 42, contacting ring 21, brush 19, brush frame 17, brush 18, contact spot 20 designated "1", plug wire 53, plug socket 54, cam contacts L34, relay R21 and line 46. The relay R21 establishes a holding circuit through the connections including main line 42, wire 55, cam contacts T16, wires 56, 57, contacts 21b, relay R21 and line 46. The energization of relay R21 closes the relay contact 21a and causes energization of magnet 26. This serves to condition the feeding devices for another line spacing operation. The circuit for energizing magnet 26 follows a path through line 42, contacts 22a and 24b, switch 50, wire 58, upper contacts 21a, magnet 26, and line 46. The magnet 26 then closes the associated contacts 26' and causes energization of the clutch magnet 1 through the following connections: line 42, contacts 22a and 24b, switch 50, wire 52, contacts 26', wiping contacts 39, 40, magnet 1, wire 45, and line 46. Line spacing operation continues in this fashion until the brush 18 strikes the contact spot 20 designated "6" on the commutator 22. Then the relay R24 is energized through a circuit including line 42, contact ring 21, brushes 19, 18, contact spot 20 designated "6", plug wire 59, plug socket 60, contacts 21d, upper contacts 24a, relay R24 and line 46. Relay R24 then operates lower contacts 24a to close a holding circuit flowing as follows: line 42, contacts 26b, cam contacts T17, wire 61, lower contacts 24a, relay R24, and line 46. It should be noted that the upper and lower contacts 24a are arranged so that the lower contacts are closed before the upper contacts open.

70 The energization of relay R24 causes the opening of the contacts 24b in series with the magnets 1 and 26, thereby discontinuing line spacing. The armature 29 (Fig. 2A) of the deenergized magnet 26 falls toward the gear 9 to engage pawls 30 and 31 with the teeth 28 to hold the platen in position.

The differential line spacing operation described hereinbefore begins shortly after the printing of the second address line at the time the cam contacts L34 close and continues until shortly before the printing of the first item.

Before the end of the third machine cycle (i. e., the first item printing operation) the relays R21 and R24 are deenergized due to the opening of the cam contacts T16 and T17. At the beginning of the next machine cycle, cam contacts L31 close to effect another line spacing operation. Four more such line spacing operations (Fig. 3) are initiated as item printing takes place. At the end of the last line spacing operation, the brush 18 rests on the contact spot 20 designated "10" and thereby relay R23 is energized to initiate spacing to the total line. The relay is energized over a circuit including line 42, contact ring 21, brushes 19, 18, contact spot designated "10", plug wire 62, plug socket 63, contact 21e, switch 64, relay 20 R23 and line 46. Relay R23 then closes a holding circuit through line 42, wire 55, cam contacts T16, wire 56, contacts 23a, relay R23, and line 46. Associated with relay R23 is another contact 23c (Fig. 4) which is normally closed but when opened by the relay initiates a series of controls in the tabulating machines similar to those effected on the occurrence of an automatic group change and total printing operation. When contacts 23c are opened, the opening of cam contacts T4 causes a deenergization of a relay UGR and the suspension of card feeding operation. Before explaining the operations brought about by the opening of contacts 23c the effect of an ordinary group change will be described briefly.

When the record cards 3a (Fig. 3A) are fed through the machine, they pass successively first under a series of upper brushes UB (Fig. 4) and then one cycle later under a series of lower brushes LB. If the group numbers perforated in the cards agree, circuits are maintained as follows: line 42, upper brush UB, group control relay GR, lower brushes LB, impulse distributors 65, card lever contacts 66 and line 46. Relays GR establish holding circuits through related holding coils GR' by the closure of associated contacts GRb along connections including line 42, cam contacts L5, contacts GRb, holding coil GR', wire 67 and line 46. Relay UGR remains energized as long as cards with similar group numbers pass under the upper and lower brushes. At this time the circuit for relay UGR flows through line 42, wire 68, relay UGR, cam contacts T4, wire 69 and line 46. During the short time that the contacts T4 are open, the circuit is maintained through contacts GRa closed by the group control relays GR' as long as they are maintained energized. This running circuit for relay UGR includes contacts 23c, a series of contacts GRa, a card lever contact OK2, wire 69 and line 46. Therefore the deenergization of relay UGR may take place in either of two ways; if the contacts 23c are opened, or if one of the group control contacts GRa is open during the breaking of the cam contact T4. The former is the case if the allotted item printing area on the form is reached before the sensing of an entire group of cards, thus requiring that another record form of the continuous sheet be brought into item receiving position. The latter is the case if the end of a card group is reached before the item printing area of a form has been used. It is possible that relay UGR may be deenergized by the simultaneous operation of both controls.

As soon as relay UGR is deenergized the asso-

ciated contact UGRa is closed to energize relay VRG. The circuit through relay VRG may be traced through line 42, wire 70, contact UGRa, relay VRG, wire 69, and line 46. Relay VRG then closes a holding circuit through line 42, wire 71, contacts R3d, wire 72, contact VRGa, relay VRG, wire 69 and line 46. When relay VRG is energized, its associated contact VRGb is closed to energize a relay AR2 through a circuit including line 42, contact VRGb, cam contacts L9, relay AR2, wire 73, and line 46. A holding circuit for this relay then flows as follows: line 42, wire 71, contacts R3d, conductor 74, wire 75, contacts AR2b, holding coil AR2H of relay AR2, wire 73 and line 46. Associated with relay AR2 is a contact AR2a which is closed when the relay is energized and thereby initiates the energization of another relay BR2 through a circuit passing along line 42, contacts VRGb, cam contacts L10, left side of contacts AR1a, relay contacts AR2a, left side of contacts BR2b, relay BR2, wires 76 and 73, and line 46. Relay BR2 then closes the right side of contacts BR2b to establish a holding circuit flowing as follows: line 42, wire 71, contacts R3d, wire 74, right side of contacts BR2b, relay BR2, wires 76 and 73 and line 46. The left side of contacts BR2b break only after the closure of the right side of these contacts.

With the closing of contacts AR2a, the spacing 30 control relay R21 is made effective when a plug wire 78 is connected between socket 77 (Fig. 4) and socket 79 (Fig. 4A). The complete circuit includes lines 42, contacts VRGb, cam contacts L10, the left side of contacts AR1a, contacts 35 AR2a, socket 77, plug wire 78, socket 79, wire 78', relay R21 and line 46. The holding circuit over relay R21 is established through line 42, wire 55, contacts T16, wires 56, 57, contacts 21b, relay R21 and line 46. Through the energization of 40 relay R21 the double contacts 21a are shifted, thereby energizing the line space relay magnet 26 over the following circuit: line 42, contacts 22a and 24b, switch 50, wire 58, upper side of contacts 21a, magnet 26, wire 45 and line 46. Then magnet 26 again closes the associated contact 45 26' to energize the clutch magnet 1 in the manner described hereinbefore. The unlocking magnet 26 releases the armature wheel 9 and magnet 1 clutches the latter to the driving means to operate the platen 3 through a feeding movement which continues until the contact brush 18 of the line selecting device 17, 22, arrives at the contact spot 20 marked "13" on the commutator disc 22. When this occurs, the feed terminating 50 relay R24 is energized over a circuit path through line 42, contact ring 21, brushes 19, 18, contact spot 20 designated "13", plug wire 80, socket 81, contacts 21d, the upper side of relay contacts 24a, relay R24, and line 46. When the relay R24 55 closes the associated lower contact 24a, it establishes a holding circuit as follows: line 42, contacts 26b, contacts T17, wire 61, the lower side of contacts 24a, relay R24, and line 46. Relay R24 then operates to open the associated contacts 24b 60 to deenergize feed magnets 26 and 1. This serves to interrupt the paper feed operation, because armature 29 of magnet 26 drops to catch the pawls 30, 31, in the teeth 28 on the armature wheel 9.

Card feeding is automatically stopped after the printing of the last item in the item printing area, and only started in operation again after a total taking cycle has been effected. When the main switch HS was closed, the usual card feeding clutch magnets KKM was energized over the

following circuit path: line 42, wire 82, magnet KKM, contacts VRGi, and line 46. Clutch magnet KKM remains energized during address and item printing and is released only during the last item printing cycle by the opening of contacts VRGi. After a progressive total is printed at the bottom of the form, the relay R25 is energized in the following circuit: line 42, contacts VRGb, cam contacts L10, right side of contacts AR1a, plug socket 83, plug wire 83a, socket 84 (Fig. 4A), 10 relay R25, contacts 26a, and line 46. A holding circuit is established through relay R25 along line 42, wire 55, contacts T16, wire 56, contacts 25a, relay R25, contacts 26a, and line 46. Relay R25 acts to close associated contacts 25b and 15 magnet 26 is energized through line 42, contacts 22a and 25b, switch 50, wire 58, contacts 21a, magnet 26 and line 46. Through the energization of magnet 26, contacts 26' are again closed to cause the energization of clutch magnet 1. The 20 armature wheel 9 is then released by magnet 26 and engaged by magnet 1 so that platen 3 is driven to space the record sheet.

When the cam contact L9 is closed, relay AR1 is made effective through connections including line 25 42, contacts VRGb, cam contacts L9, contacts BR2a, relay AR1, wire 73, and line 46. The holding circuit through relay AR1 flows as follows: line 42, wire 71, contacts R3d, wires 74 and 75, contact AR1b, holding coil AR1H of relay AR1, 30 wire 73, and line 46. Upon energization of relay AR1, the contacts AR1a are shifted and socket 83 again becomes alive to energize relay R25 as explained hereinbefore. In addition to this, the relay BR1 is energized through line 42, relay 35 contacts VRGb, cam contacts L10, the right side of contacts AR1a, left side of contacts BR1b, relay BR1, wires 76 and 73, and line 46. A holding circuit over relay BR1 flows through line 42, wire 71, contacts R3d, wire 85, right 40 side of contacts BR1b, relay BR1, and wires 76 and 73 to line 46. As soon as cam contact L18 is closed, relay R3 is energized over a circuit through line 42, wire 86, cam contacts T1, cam contacts L18, relay contacts BR1a, relay R3 and 45 line 46. Relay R3 then closes a holding circuit through the closed contacts R3a. Energization of relay R3 serves to open the associated contacts R3d and thereby deenergize the group control enforcing relays VRG, BR1, BR2, AR1 and 50 AR2. Then the card feed clutch magnet KKM is again energized through line 42, wire 82, magnet KKM, contacts VRGi and line 46, thereby initiating card feeding operation.

It is mentioned hereinbefore that paper feeding is initiated by relay R25 when this relay is energized through connections including plug sockets 83 and 84. Such feeding movement continues until relay R22 is energized by a circuit initiated when brush 18 strikes the contact spot 60 20 designated "17". The circuit through the plug spot "17" may be traced through line 42, contact ring 21, brushes 19, 18, contact spot 20 designated "17", plug wire 87, socket 88, relay R22 and line 46. The relay closes a holding circuit 65 through line 42, contacts 26b, cam contacts T17, wire 89, switch 90, wire 91, contacts 22b, relay R22 and line 46. Relay R22 is made effective and contacts 22a are opened to deenergize magnets 1, 26 and 27. Armature 29 of magnet 26 70 then drops to engage wheel 9 to lock it and stop operation of the platen. Armature disc 14 associated with magnet 13 is also stopped by the action of magnet 27 when the tooth 32 strikes the pawls 33 and 34 on armature 35. Through the 75

energization of the relay R22 the associated contact 22c is closed to energize resetting magnet 36. This magnet attracts armature 14 to couple the brush holder 17 with the continuously rotating shaft 7 so that the holder is restored to normal position.

Disc 14 and armature 35 (Fig. 2A) are shaped so that contacts 27' are held closed throughout most of the time that the disc is rotating. Contacts 27' are not opened while the end of the armature is resting on the concentric part of the periphery of the disc 14 and they open normally a short time before projection 32 passes between the locking faces of pawls 33 and 34. As soon as contacts 27' open, the brush resetting magnet 36 is deenergized. This arrangement makes it possible for magnet 36 and armature 14 to be disengaged shortly before the armature is locked in normal position. The circuit through the resetting magnet 36 flows through line 42, wire 41, lower side of contacts 22c, contacts 27', wiping contacts 39, 40, magnet 36 and line 46.

When the armature disc 14 is locked in normal position (Fig. 2A), the brush holder 17 is again in the starting position wherein brush 18 rests on contact spot 20 designated "0" (Fig. 4A) and relay R26 is energized through line 42, contact ring 21, brushes 19, 18, contact spot 20 designated "0", wire 92, contacts 23d, switch 93, relay R26, and line 46. When the relay R26 is energized it opens the associated contacts 26a and 26b to deenergize relays R22, R24 and R25. Relays R22 and R24 release contacts 22a and 24b so that they again close, and the clutch releasing magnet 26 is energized over a circuit including line 42, contacts 22a, 24b, switch 50, conductor 58, upper side of contacts 21a, magnet 26, and line 46. Through the energization of magnet 26, the feed clutching magnet 1 is energized by closed contacts 22a, 24b, switch 50, wire 52, armature contacts 26', and through magnet 1 to line 46. The brush releasing magnet 27 is also energized through the closure of contacts 22a and switch 44. Coupling magnet 13 is also made effective through the closure of upper contacts 22c and switch 48. Because of these operations, the armature wheel 9 is unlocked so that clutch magnet 1 is adapted to drive the platen 3. Because the magnet 27 releases the armature disc 14, the brush coupling magnet 13 is also effective so that the brush holder is moved along with the armature wheel 9. This movement of the brush holder continues until the brush 18 reaches the contact spot 20 designated "6" showing that the next record form is presented with the first item printing receiving line in printing position. It may be noted that on this second form a record of the address is not necessary as it is a continuation of the previous form.

When the brush holder 17 reaches the commutator position designated "6", then the relay R24 is again energized because relay R21 has been held energized by its holding circuit and contacts 21d are closed. Relay R24 sets up its own holding circuit through lower contacts 24a. Since contacts 24b are opened when magnet R24 is energized, magnets 1 and 26 are again deenergized so that armature wheel 9 and the connected platen 3 are brought to rest. The remainder of the record cards comprising the card group under consideration are then sensed until a group change is initiated by the appearance of the first card of the following group under the upper brushes UB. The disagreement of group numbers on two successive cards is manifested by the de-

energization of one or more relays GR so that the control relay UGR is deenergized as soon as cam contact T4 opens. The relay VRG is then energized as mentioned hereinbefore and held energized by its holding circuit. The card feed clutch magnet KKM (Fig. 4) is deenergized at this time so that card feeding is stopped.

Relay R21 is energized through the circuit including contacts VRGb and the plug connections including plug wire 78. This relay closes associated upper contacts 21a (Fig. 4A) to energize magnet 26 and close armature contact 26' so that the clutch magnet 1 is again energized to start a feeding operation. Paper feeding continues until the contact brush 18 touches the contact spot 20 designated "13". Then the record sheet is in a total printing position and relay R24 is energized and related contacts 24b open to deenergize magnets 1 and 26, so that the sheet feeding operation is terminated. During the movement of the record sheet from the position corresponding with the "6" designation on the commutator to the "13" spot on the commutator, it passes through the "10" position wherein the brush 18 passes over the contact spot 20 designated "10". However, no energization of the connected relay R23 results because the previous group change operation served to energize relay R21 and thereby open contacts 21e which are in series with relay R23.

After the printing of the group total, relay R25 is again energized and the associated contact 25b is closed to energize magnets 1 and 26, so that feeding is started again and continues until brush 18 reaches the contact spot 20 marked "17". Then relay R22 is energized and remains in this condition by means of the connections through switch 90, cam contacts T17 and relay contacts 26b. The opening of contacts 22a and 22c serve to deenergize magnets 1, 13, 26 and 27 while magnet 36 is energized. Brush holder 17 is then restored to the starting position by means of the connections established by energized magnet 36. Although the brush 18 then touches the contact spot 20 designated "0", relay R26 is not energized because relay R23 is not effective to close contacts 23b. This brings the feeding devices back to a starting position so that operations may be initiated under control of the following group of record cards.

There are times when it is desired to use a form for each item recorded on the separate record cards. When such control is desired, a single plugging connection is made with a contact spot 20, such as the connection made with spot designated "17" in Fig. 4A. Furthermore, the positions of switches 50, 51, 64, 90 and 93 are reversed so that switches 50, 51 and 93 are opened and switches 64 and 90 are placed in the closed positions shown by dotted lines in Fig. 4A. The other switch 94 shown at the top of Fig. 4A is closed when single item recording is desired. Then paper feeding is operated each time an item is printed and is interrupted when the brush holder 17 carries the brush 18 into contact with the spot 20 plugged to the feed control connections. These connections serve to bring the brush holder back to the starting position.

The amount of space between items may be determined automatically by setting controls for selecting one, two or three spaces between record lines on forms. Referring to the top of Fig. 4A, it is seen that in addition to the switch 51, two other similar switches 51' and 51'' are coordinated with cam contacts L32 and L33 which

have the same effect as the other cam contact L31. The cam contacts L31 and L32 and L33 (Fig. 5) are timed in such a way that they become operative in succession to initiate one, 5 two or three line spacing operations by energizing the connected unlocking magnet 26 one, two or three times within a single operating cycle. Operation of this magnet 26 involves a corresponding energization of the clutching magnet 1 to drive the platen 3 through the required 10 distance.

The general construction of the item and total printing devices used in the machine are well known in the art and described in Patent 15 1,976,617, consequently there will be given herein only a brief explanation of such parts as are helpful to an understanding of the present invention.

As the cards pass the lower brushes the per- 20 forated index points instantaneously close circuits through the proper lower analyzing brushes LB to energize accumulator magnets AM (Fig. 6). As usual, the timed energization of these magnets control mechanism for entering amounts 25 in the accumulator corresponding to the card reading. Referring to Fig. 6 it is seen that magnet AM attracts the pivoted armature 176 and releases a lever 173 which slides a toothed driving clutch collar 171 into engagement with the 30 clutch collar 179 on accumulator gear 180. The gear is turned a differential amount according to the time that magnet AM is energized. Gear 180 meshes with a gear 209 carrying brushes 210 which cooperate with commutator segments 35 211 to give a reading of the total amount accumulated on total taking operations. This total reading device is set forth in greater detail in the Lake Patent 1,379,268 granted May 24, 1921.

When any magnet AM is energized, it causes 40 contacts to close, energizing a printer magnet PM (Fig. 7) to select the type corresponding to the entered data. In this fashion the accumulated or entered items may be listed.

In Fig. 7 is shown the printing mechanism 45 through which the type bar 212 is positioned relatively to the platen 3 to bring the proper type 218 opposite the platen. The listing shaft 265 driven by the tabulating motor TM is provided with a cam 273 cooperating with a roller 311a 50 carried by an arm 311 operatively connected to a shaft 308. As the cam rotates, shaft 308 is rocked in a clockwise direction and an arm 307 secured thereto and linked at its free ends to printing cross-head 304 serves to raise the type bars 212 55 in synchronism with the movement of the record cards past the analyzing brushes so that the type 218 successively pass the printing position opposite platen 3. The type bar 212 is arrested under control of printing magnet PM, which, 60 when energized, attracts its armature 221 and through a call wire 220 releases a latch member 211, normally holding a stop pawl 223.

When the pawl is so released, it is spring operated to engage the ratchet teeth 216 formed on 65 the type bar 212 to prevent further upward movement of the type bar, thus holding a particular type 218 in front of hammer 224 which is provided to impel the type against the platen.

Although this specification fully discloses the 70 novel features of the invention, it will be understood that various omissions, substitutions and changes in the form and details of the devices illustrated may be made by those skilled in the art without departing from the spirit of the invention. It is the intention, therefore, to be 75

limited only as indicated by the scope of the following claims.

What is claimed is:

1. In a machine for feeding a record sheet to receive printing impressions on predetermined lines, means for holding said sheet, a driving means, a magnetic clutch for engaging said driving means with said holding means to feed said sheet, means for disengaging said clutch to stop sheet feeding, a settable electrical contact device, 10 means for moving said device in synchronism with the sheet feed, means under control of said device for operating said clutch and said disengaging means at predetermined line positions on the sheet to limit the print receiving area thereon. 15

2. In a machine for feeding a record sheet to receive impressions on predetermined lines, means for holding said sheet, a driving means, 20 means for engaging said driving means with said holding means to feed said sheet, means for disengaging said driving means to stop sheet feeding, a line selecting commutator with a movable brush and pluggable contact points, each point relating to a line on said sheet, means for moving said brush in synchronism with the sheet feed 25 to touch one after another of said points, relays plugged to certain of said points, and means under control of said relays for operating said clutch and said disengaging means at predetermined line positions on the sheets to determine 30 the print receiving area thereon.

3. In a machine for feeding record material, means for feeding said material, means for stopping said feeding means, relays for controlling said feeding and stopping means, a stationary insulation disc, a series of contact points arranged in a circle on said disc, a contact brush pivoted at the center of said disc and contacting with said points to make them effective successively, means for moving said brush as the material is fed, 40 means for plugging said control relays to selected points to be effective at predetermined times during feeding, and other means for initiating operation of said feeding means when it is stopped by said relays. 45

4. In a machine for feeding a record sheet divided into line spaces, means for feeding said sheet, means for locking said feeding means, means for releasing said locking means momentarily for a line spacing operation, other means 50 for releasing said locking means for a long feeding operation, relays for controlling both of said releasing means, a line selecting commutator with a movable brush and pluggable contact points, each point relating to a line on said sheet, means for controlling the movement of said brush by said sheet feeding means to move from point to point to make the points effective serially, and plug connections between said relays and selected points for operating said relays to initiate line 55 spacing and long feeding operations at predetermined positions on the sheet.

5. In a machine for feeding a record sheet, a platen on which said sheet is fed, driving means, a clutch between said platen and said driving means, a magnet for controlling said clutch, contacts in series with said magnet, a latch for locking said clutch and operating said contacts, a magnet for operating said latch, and means for energizing said latch magnet automatically at 65 desired positions of said record sheet, whereby said latch is released and said contacts are closed to make the clutch magnet effective.

6. In a machine for feeding a record sheet with predetermined lines on which printing is to be 75

- effected, means for line spacing and long spacing said sheet, a line selector, means under control of said line selector for controlling the lines at which said means is effective for line spacing and 5 long spacing, a clutch between said spacing means and said selector, and means for operating said clutch while said spacing means is effective.
7. In a machine for feeding a record sheet with predetermined lines on which printing is to be effected, means for line spacing and long spacing said sheet, a line selector, means under control of said selector for selecting the lines on which said means is automatically effective for line spacing and long spacing, connections between 10 said selector and said spacing means for moving them in synchronism, a driving means, a clutch between said driving means and said selector, and means for automatically operating said clutch to restore said line selector when the end of the 15 sheet is reached.
8. In a machine for feeding a record sheet with predetermined lines on which printing is to be effected, means for line spacing and long spacing said sheet, a line selector, means under control 20 of said selector for selecting the lines on which said means is automatically effective for line spacing and long spacing, connections between said selector and said spacing means for moving them in synchronism, a driving means, a clutch 25 between said driving means and said selector, a magnet for operating said clutch, contacts in series with said magnet, a latch for holding said clutch in normal position and operating said contacts, a magnet for operating said latch, and 30 means for automatically energizing said latch magnet when printing is completed on a sheet, whereby said latch is released and said contacts are closed to make the clutch magnet effective to 35 operate the clutch and restore said selector.
9. In a machine for feeding a record sheet with predetermined lines on which printing is to be effected, means for line spacing and long spacing said sheet, a line selector, means under control 40 of said line selector for controlling the lines at which said means is effective for line spacing and long spacing, a magnetic clutch between said spacing means and said selector, a magnet for operating said clutch, and means for energizing said magnet while said spacing means is effective.
10. In a machine for feeding a record sheet with predetermined lines on which printing is to be effected, means for line spacing and long spacing said sheet, a line selector, means under control 45 of said selector for selecting the lines on which said means is automatically effective for line spacing and long spacing, a driving means, and three magnetic clutches mounted coaxially, the first clutch connecting said spacing means to the driving means, the second clutch connecting said selector to said spacing means, and the third clutch connecting said selector to said driving means for restoration.
11. In a machine for feeding a record sheet to receive printing impressions on predetermined lines, means for feeding said sheet, means for controlling said feeding means to cause line spacing, devices for controlling said feeding means to cause long feeding, means for stopping said feeding means, a selector with a plurality of control effecting positions each related to a line 50 on said sheet, a movable member cooperating with said selector and adapted to move from position to position to make said positions effective seriatim, means for moving said member as the sheet is fed, means for associating said line space control means, said long feed control devices and said stopping means with predetermined positions on said selector, and means under control of said member when cooperating with said predetermined positions for making said line space control means, said long feed control devices and said stopping means effective at 55 predetermined lines on said sheet.
12. In a machine for feeding a record sheet, a platen on which said sheet is fed, a driving means, a clutch between said platen and said driving means, a magnet for controlling said clutch, contacts in series with said magnet, a latch cooperating with said clutch and said contacts, a magnet for controlling said latch, a plurality of cam contacts wired in parallel with each other and all in series with said latch magnet, switches 60 associated with said cam contacts for making one or more of them effective whereby said cam contacts energize said latch magnet to release the latch and close the first mentioned contacts to energize said clutch magnet one or more times 65 during each cycle.
13. In a machine for feeding a continuous sheet divided into bill forms with prearranged lines for receiving address, item and total print impressions, a platen on which said sheet is fed, a driving means for said platen, a clutch for connecting said platen to the driver, a line selector commutator with a movable brush and pluggable contact points, each point relating to a line on 70 said forms, a lock for said clutch, a relay selectively plugged to one of said contact points and effective to release said lock and render said clutch effective after a predetermined number of lines of address print, another clutch between said brush and the platen clutch for synchronizing the movement of the brush with the movement of the sheet, a second relay selectively plugged to one of said contact points and effective to reengage said lock and stop the sheet in position to record the first item, means for operating the 75 first mentioned clutch to effect line spacing, a third relay selectively plugged to one of said contact points and effective to operate the first mentioned clutch and the lock to feed the sheet after an item is recorded at the bottom of the item printing area, other means for operating the first mentioned clutch to feed before the bottom of the area is reached when a total is to be printed, secondary plug connections from a selected one of said contact points to said second relay to make it effective to reengage said lock and stop the sheet in position to record a total, means for making the first mentioned relay effective to feed the sheet after total recording, a fourth relay selectively plugged to one of said contact points and effective to reengage said lock and stop the sheet with the next form in position to record the first address line, a third clutch between said brush and the driving means controlled by said fourth relay to restore said brush, a lock for said third clutch for stopping said brush in the normal position, a magnet under control of said fourth relay for making said lock effective and a fifth relay plugged to the contact point touched by said brush in the normal position for conditioning the first mentioned clutch to resume sheet feeding.

WALTER P. SCHARR.
